Primary Examiner — Jack Reickel*Assistant Examiner* — Michael A Kervin(74) *Attorney, Agent, or Firm* — Woodard Emhardt Henry Reeves & Wagner LLP(57) **CLAIM**

The ornamental design for a tool crown, as shown and described.

DESCRIPTION

FIG. 1 is a perspective view of the tool crown, according to one embodiment.

FIG. 2 is another perspective view of the tool crown of FIG. 1.

FIG. 3 is a first side view of the tool crown of FIG. 1.

FIG. 4 is a second side view of the tool crown of FIG. 1.

FIG. 5 is another perspective view of the tool crown of FIG. 1.

FIG. 6 is a perspective view of the tool crown, according to one embodiment; and,

FIG. 7 is another perspective view of the tool crown of FIG. 6.

The broken lines in the drawings illustrate subject matter which forms no part of the claimed design.

1 Claim, 6 Drawing Sheets(56)
